UNITED STATES PATENT OFFICE.

THOMAS LEGGETT STURTEVANT, OF QUINCY, AND THOMAS JOSEPH STURTEVANT, OF WELLESLEY, MASSACHUSETTS, ASSIGNORS TO STURTEVANT MILL COMPANY, OF PORTLAND, MAINE, A CORPORATION OF MAINE.

ENGINE-LUBRICATING DEVICE.

No. 834,498.

Specification of Letters Patent.

Patented Oct. 30, 1906.

Application filed March 17, 1906. Serial No. 306,658.

To all whom it may concern:

Be it known that we, THOMAS LEGGETT STURTEVANT, residing at Quincy, and THOMAS JOSEPH STURTEVANT, residing at 5 Wellesley, in the county of Norfolk and State of Massachusetts, citizens of the United States, have invented or discovered certain new and useful Improvements in Engine-Lubricating Devices, of which the following 10 is a specification, reference being had therein to the accompanying drawings.

This invention relates to certain improvements in engines, and has for its object to provide means whereby the crank-shafts, pitman-bearings, and also the engine-cylinders 15 may be properly lubricated.

The invention is more particularly intended for use in connection with gas or explosion engines, but is also adapted for use in connection with engines of other kinds.

In carrying the invention into effect the crank-shaft casing is adapted to serve as a receptacle for oil, which will preferably be fed thereto from a float-controlled oil-cup or oil-cups in such a manner that an oil-level will be maintained within the crank-casing at a point to permit the rotating cranks to dip slightly into the oil at the bottoms of their strokes, so that when the cranks are in rapid rotation 20 they will splash into the oil in such a manner as to raise a mist or fog of oil within the crank-casing, and the oil will thereby be sprayed into the bearings of the crank-shaft and also into concaved recesses or receptacles 25 with which the crank-shaft is provided, said concaved recesses communicating by suitable passages or ducts with chambers in the cranks and said chambers also communicating by suitable passages or ducts with the 30 pitman-bearings on the cranks. The pitmen are preferably provided with longitudinal passages or ducts, through which the oil can pass to the pitman-bearings in the pistons, and from these points the oil will work into 35 annular pockets formed in the pistons and communicating by suitable passages or ducts with grooves formed in the periphery of the pistons, so that the oil can spread over the exterior surfaces of the pistons and the interior surfaces of the cylinders in which the 40 pistons work. Thus when the cranks are in

rapid rotation and the oil is sprayed about in the piston-chamber it will work into the concaved recesses or chambers with which the crank-shaft is provided and will be forced 55 outward centrifugally from said chambers to the chambers in the cranks and thence through the ducts in the piston-rods to the pistons. The chambers or recesses in the crank-shaft are preferably provided with 60 screens, so that impurities or particles in the oil will be prevented from entering into and thereby clogging the oil passages or ducts.

In the accompanying drawings, Figure 1 is a sectional view showing an engine crank-shaft casing and crank-shaft constructed in accordance with the present invention; and Fig. 2 is a sectional view on line 2 2, Fig. 1, and at right angles thereto.

Referring to the drawings, 12 denotes a 70 crank-shaft casing which is provided with openings 13, which in practice will communicate with the chambers of the cylinders to be attached to the said crank-shaft casing.

14 denotes a crank-shaft in the solid metal 75 of which are seated rings 15, forming parts of ball-bearing casings and between which and the outer rings 16 are interposed balls 17 to constitute ball-bearings. These ball-bearings may be of any well-known or suitable construction and will preferably be of that class in which coil-springs are interposed between the balls to prevent them from rattling. The crank-shaft is provided with oil-receiving recesses or chambers 18, open at both ends and 80 having sloping or concave walls, said chambers communicating with oil passages or ducts 19 20, which in turn communicate with chambers 21, formed in the cranks 22, said chambers 21 having oil-outlet ducts or passages 23, by which oil can escape to the outer surfaces of the said cranks to lubricate the joints between the cranks and pitmen. 85

The pitmen 24 are provided with longitudinal oil ducts or passages 25, through which 90 the oil will be centrifugally forced outward from the chambers 21 on the cranks 22 to each of the pitman-pins 26, secured in the pistons 27, reciprocating within the cylinders 41 in the usual manner. Each of the pistons 95 is preferably provided at its recessed lower part with an annular oil-pocket 28, commu-

nicating by suitable ducts or passages 29 with an oil-receiving groove 30, so that the oil which lubricates each pitman-pin 26, and more or less of which will work outward from the said pin, will creep down the wall of the chamber in the base of the piston and be received in the annular oil-pocket 28 and will pass thence through the ducts or passages 29 to the oil-receiving groove 30, from whence it will spread over the outer surface of the piston and the inner surface of the cylinder in which the piston is reciprocated.

To prevent impurities or solid particles in the oil from entering the oil ducts or passages referred to, the oil-chambers 18 in the crank-shaft are preferably provided with woven-wire screens 31.

The oil is fed to the chamber of the crank-casing from an oil-cup or oil-cups 32, communicating by pipes 33 with the chamber of the crank-casing, said oil-cups being supplied with oil from a reservoir or reservoirs 34, communicating by a pipe or pipes 35 with the said oil-cups, and the level of oil within the latter, as also the level of the oil within the chamber in the crank-casing, is governed by valves 36, controlled by floats 37, so that a level of oil may be maintained within the crank-casing suitable to permit the cranks to dip into the same slightly when they are at the bottoms of their strokes.

The four-crank crank-shaft herein illustrated is preferably formed in two parts or sections connected together by bolts 38, although this crank-shaft might be made in four parts or sections or in one piece, if desired. The fly-wheel 39 is, as herein shown, attached to the crank-shaft by means of screw-bolts 40.

From the foregoing it will be apparent that the invention provides means whereby an unfailing supply of oil may be fed to the crank-casing, in which the oil may be maintained at any desired level, so that the rotating cranks will splash therein, such splashing of oil serving to lubricate the ball-bearings, the cases of which open into the chamber of the crank-casing and which ball-bearing cases are seated in the solid metal of the crank-shaft.

It will also be apparent that the splashing of oil within the chamber of the crank-casing will cause more or less of the oil to be supplied to the open-ended chambers 18, formed in the crank-shaft, and from which chambers the oil will be forced outward centrifugally through the ducts or passages shown and described to the chambers 21 in the cranks and thence outward through the ducts in the pitmen to the outer bearings of the latter in the pistons and from which outer bearings the oil will be spread or be conducted to the outer surfaces of the pistons and the interior surfaces of the cylinders, as hereinbefore described.

Having thus described our invention, we

claim and desire to secure by Letters Patent—

1. The combination with an engine crank-case adapted to contain a liquid lubricant, of automatic means for maintaining a supply of oil in said crank-case at any desired level, a crank-shaft rotating in said crank-case, a crank or cranks carried by said shaft, and adapted to dip into the oil to be contained in said crank-case, and means, rotating with the said crank-shaft, for distributing oil by centrifugal action when the said shaft is in rotation.

2. The combination with an engine-case adapted to contain a liquid lubricant, of means for maintaining a supply of oil in said crank-case at any desired level, a crank-shaft rotating in said crank-case, a crank or cranks carried by said shaft and adapted to dip into the oil to be contained in said crank-case, means, rotating with the said crank-shaft, for distributing oil by centrifugal action when the said shaft is in rotation, and ball-bearings supporting said crank-shaft and open to the interior of the said crank-case so as to be lubricated by the oil splashed about therein by the rotating crank or cranks.

3. The combination with an engine crank-case adapted to contain a liquid lubricant, of a sectional crank-shaft journaled therein and carrying a plurality of cranks, means for maintaining a supply of oil in said crank-case at any desired level, so that said cranks can dip into the oil at or near the bottom of their strokes, and means, rotating with the said crank-shaft, for distributing oil to parts eccentric to said crank-shaft.

4. The combination with an engine crank-case adapted to contain a liquid lubricant, of a sectional crank-shaft journaled therein and carrying a plurality of cranks, means for maintaining a supply of oil in said crank-case at any desired level, so that said cranks can dip into the oil at or near the bottom of their strokes, means, rotating with the said crank-shaft, for distributing oil to parts eccentric to said crank-shaft, and means, also rotating with said crank-shaft, for screening or purifying the oil to be distributed.

5. The combination with an engine crank-case adapted to contain a liquid lubricant, of means for supplying oil to said crank-case, a crank-shaft journaled in said case and having one or more open-ended oil-receiving chambers, one or more chambered cranks rotating with the said crank-shaft, said open-ended chambers being adapted to receive oil splashed about in the chamber of the said case by said crank or cranks, passages or ducts through which oil may be centrifugally forced from said open-ended chambers to the chambers in the cranks, and means for permitting the passage of oil from the said crank or cranks outward, by centrifugal action, to lubricate other parts.

6. The combination with an engine crank-case adapted to contain a liquid lubricant, of means for supplying oil to said crank-case, a crank-shaft journaled in said case and having one or more open-ended oil-receiving chambers, one or more chambered cranks rotating with said crank-shaft, said open-ended chambers being adapted to receive oil splashed about in the chamber of the said case by said crank or cranks, passages or ducts through which oil may be centrifugally forced from said open-ended chambers to the chambers in the cranks, means for permitting the passage of oil from the said crank or cranks outward, by centrifugal action, to lubricate other parts, and means in said oil-receiving chambers to screen the oil so that the said oil passages or ducts will not become clogged.

7. The combination with an engine crank-case, adapted to contain a liquid lubricant, and means for supplying such lubricant to said crank-case, of a crank-shaft rotating in said crank-case, one or more cranks on said crank-shaft, and means on said crank-shaft for centrifugally supplying oil to said crank or cranks.

8. The combination with an engine crank-case, adapted to contain a liquid lubricant, and means for supplying such lubricant to said crank-case, of a crank-shaft rotating in said crank-case, one or more cranks in said crank-shaft, means on said crank-shaft for centrifugally supplying oil to said crank or cranks, and means, also on said crank-shaft, for screening or purifying the oil thus supplied.

9. The combination with an engine crank-case, adapted to contain a liquid lubricant, and one or more cranks rotating in said crank-case, of float-controlled oil-supplying means for maintaining a level of oil in said crank-case suitable to permit said crank or cranks, when in rotation, to dip into the oil more or less.

10. The combination with an engine crank-case, adapted to contain a liquid lubricant, and one or more chambered cranks rotating in said crank-case, of float-controlled oil-supplying means for maintaining a proper level of oil in said crank-case to permit the said

crank or cranks to dip into the oil more or less, and means for centrifugally supplying oil to the chamber or chambers of said crank or cranks.

11. The combination with an engine crank-case, adapted to contain a liquid lubricant, and one or more chambered cranks rotating in said crank-case, of float-controlled oil-supplying means for maintaining a proper level of oil in said crank-case to permit the said crank or cranks to dip into the oil more or less, means for centrifugally supplying oil to the chamber or chambers of said crank or cranks, and means for permitting the passage of oil from said crank or cranks outward to lubricate other parts.

12. The combination with an engine crank-case adapted to hold a liquid lubricant, of a sectional or two-part crank-shaft journaled therein and having four cranks, antifriction or ball bearings seated in the solid metal of said shaft, float-controlled means for supplying lubricant to said crank-case, and means on said shaft for centrifugally supplying the lubricant to the cranks carried by said shaft.

13. The combination with a four-cylinder-engine crank-case, adapted to hold a liquid lubricant, of a sectional or two-part crank-shaft journaled therein and having four cranks, antifriction or ball bearings seated in the solid metal of said shaft, float-controlled means for supplying lubricant to said crank-case, means on said shaft for centrifugally supplying the lubricant to the cranks carried by said shaft, and means for centrifugally supplying the lubricant to the pitmen and pistons operated by said cranks.

14. The combination with an engine crank-case adapted to hold a liquid lubricant, of a two-part crank-shaft having four cranks, ball-bearings supporting said crank-shaft, and means for maintaining any desired oil-level in said crank-case so that said cranks may dip into the oil when in rotation.

In testimony whereof we affix our signatures in presence of two witnesses.
